AUTOMATIC STOKER

Nathan M. Lower, Erie, Pa.

Application April 28, 1939, Serial No. 270,619

27 Claims. (Cl. 119—104)

This invention relates generally to mechanical stokers for delivering fuel from a source of supply to a furnace firebox, and more particularly to stokers of the type employing pneumatic fuel conveying means.

It is an object of the invention to provide a novel stoker, of the type in which fuel is pneumatically conveyed, that is automatic in operation, easily installed, economical, and reliable in operation.

Another object of the invention is to provide a novel stoker of the type described in which the fuel is preheated by a carrier fluid withdrawn from the furnace.

In such stokers difficulty has been experienced in the past in conveying wet coal and particularly wet coal containing a large amount of slack since even a very small percent of water in the coal gradually clogs the elbows in the fuel pipe and eventually the straight sections of the pipe. Local heat applied at the elbows will maintain that individual area clean but will not prevent eventual clogging of other sections of the pipe. It is consequently another object of my invention to provide an improved and simple stoker construction in which wet coal containing a considerable amount of slack can be pneumatically conveyed in a convenient and efficient manner.

Clogging of the fuel feed pipes is particularly troublesome where the bin is of necessity a considerable distance from the furnace and it is a further object of my invention to provide a simple and efficient construction which will eliminate clogging where wet coal is pneumatically conveyed through a coal feed pipe of considerable length.

Another object of my invention is to provide simple and effective means for insuring a continuous supply of fuel from a fuel bin to a stoker trough disposed therebeneath, in which trough is provided conveying means for advancing the fuel therethrough. Coal will when slightly damp arch over the conveying means or in some cases a chasm will be formed above the conveying means, and the coal in the bin on either side of the conveying means will remain dormant. It is, therefore, an additional object of the invention to provide means that will render the fuel in the bin that is beyond the immediate zone of action of the conveyor available to the conveyor.

Still another object of the invention is to provide in a stoker for conveying fuel from a fuel bin to a furnace, means eliminating dust in the fuel bin and leakage of dust from the stoker.

Another object of the invention is to provide

novel means automatically interrupting the operation of the motor for the mechanical fuel conveying means of the stoker when a clog occurs and to provide means signalling cessation of the stoker conveying means.

Another object of the invention is to provide means for automatically interrupting the operation of the motor for the fan of a pneumatic fuel conveying mechanism when a clog occurs in the fuel feed piping.

Still another object of the invention is to provide a novel combination and arrangement of elements for automatically operating a stoker intermittently.

Another object of the invention is to provide a novel aperiodically operated stoker of the type in which fuel is pneumatically conveyed, that will efficiently convey wet fuel without clogging of the fuel tube.

Another object of the invention is to provide a novel coal feeding pipe, having a movable section arranged to be swung out of axial alignment with the stationary sections of the coal feeding pipe and having means eliminating leakage of coal dust between the adjacent ends of the movable coal pipe section and the stationary sections of the coal pipe.

Other and further objects and advantages of the invention, residing in the construction of parts, the combination and relation of elements will become apparent from the following description when read in connection with the accompanying drawings, in which

Figure 1 is a view in elevation of a furnace and fuel bin showing the novel stoker applied thereto, parts being broken away and shown in section;

Figure 2 is a plan view of a portion of the stoker fuel feed tube and the pipe for withdrawing hot gases from the furnace, parts being broken away;

Figure 3 is an isometric view of a portion of the stoker fuel tube provided with a movable section and including a novel arrangement for eliminating leakage of fuel dust;

Figure 4 is a sectional plan view of the fuel bin and stoker taken on the irregular line 4—4 of Figure 1;

Figure 5 is a sectional view taken on the line 5—5 of Figure 4;

Figure 6 is a sectional view taken on the irregular line 6—6 of Figure 4, parts thereof being shown in elevation;

Figure 7 is a sectional view taken on the line 7—7 of Figure 4;

Figure 8 is a sectional view on the line 8—8 of Figure 4, parts thereof, being shown in elevation;

Figure 9 is a sectional view taken on the line 9—9 of Figure 8, parts being shown in elevation;

Figure 10 is a fragmentary sectional view of the construction shown in Figure 9 in a different phase of its operation;

Figure 11 is a sectional view taken on the line 11—11 of Figure 4;

Figure 12 is a sectional view taken on the line 12—12 of Figure 4;

Figure 13 is a sectional enlarged view of the stoker clog control mechanism shown on Figure 1;

Figure 14 is a sectional view on the line 14—14 of Figure 13 with the electrical connections to a motor shown diagrammatically;

Figure 15 is a view of the control mechanism shown in Figure 13 in a different phase of its operation;

Figure 16 is a fragmentary sectional plan view of a modified form of the stoker drive mechanism shown in the preferred form of the invention; and

Figure 17 is a sectional view taken on line 17—17 of Figure 16 showing the drive mechanism in detail and a control mechanism therefor, the electrical connections being shown diagrammatically.

In the drawings, referring to Figure 1, a furnace is shown at F, which for purpose of illustration is shown with a pair of firedoors 11 and 11'; and a pair of downcomer coal delivery pipes 12 and 12'; entering the furnace above the level of the doors 11 and 11'; respectively. As the description proceeds it will become apparent that the invention is equally applicable to a furnace having one, or more than two separate fuel entrances, or to a battery of furnaces. A fuel bin is shown at B, from which the novel stoker S delivers fuel to the furnace F.

The bin B may be of any desirable shape, that shown in the drawings being by preference, cylindrical. The bottom 13 of the bin is preferably disposed above the level of the furnace room floor 10, thereby making certain mechanism on the underside of the bottom 13, hereinafter described in detail, freely accessible. Preferably the bin bottom 13 is in the form of an iron casting, since an iron casting is cheap to make and does not rust. It is provided with a depending elongated trough 14 integrally formed therewith. The trough 14 is arranged to receive coal from the bin B and as best shown in Figure 4 is disposed to one side of the center of the bin bottom 13. It is obvious, of course, that the trough 14 could if desired be formed as a separate casting or as a fabricated member and be secured in any suitable manner to the bin bottom 13.

For convenience in description and definite orientation of parts, the terms "forward" and "front," and "rearward" and "rear" will be used relative to the direction of travel of the coal from the bin to the furnace. The trough 14 is open at its forward end and registers with an opening 15 in the upright wall 16 of the bin B, as best shown in Fig. 6. Embracing the opening 15 is a compartment or box 17 which is secured in any suitable manner to the outer surface of the upright wall 16 of the fuel bin B. The wall of the compartment 17 opposite the opening 15 is provided with an opening 18 arranged to receive one end of a conduit 19. The conduit 19 extends forwardly from the compartment 17 in axial alignment with the trough 14 and is supported at its forward end in any suitable manner on the furnace room floor 10 and at its rearward end on a

platform 20 secured to the compartment 17. The supports for the respective ends of the conduit 19 are preferably provided with the vibration dampers 21. A dust tight seal 22 of any suitable form is provided at the point of entrance of the conduit 19 into the compartment 17.

Coal entering the trough 14 is conveyed forwardly therethrough into the compartment 17 by a screw conveyor 23 mounted in the trough 14 and extending through the opening 15 into the compartment 17. A screw conveyor 24, of larger diameter than the screw conveyor 23, is spliced to the forward end of the screw conveyor 23 as at 25 and conveys the fuel from the compartment 17 forwardly through the conduit 19 to a discharge opening 26 near the forward end of the conduit 19. The screw conveyor 24 is provided at its forward end between the discharge opening 26 of the conduit 19 and its forward end with a reverse flight 27, best shown in Fig. 7. The reverse flight 27 loosens the coal, preventing packing thereof at the forward end of the conduit 19 and aids in urging the coal through the discharge opening 26.

The coal screw conveying system, comprising the spliced screw conveyors 23 and 24, is driven from its forward end through gearing housed in the gear casing 28, which casing is rigidly secured to the forward end of the conduit 19. A dust seal 29, of any suitable design, is provided in the forward end of the conduit 19 between the end of the reverse flight 27 and the gear casing 28 to prevent coal dust from entering the gearing. The gearing includes a gear 30 splined on a short shaft 31, which in turn is operatively connected with the hub of the screw conveyor 24.

The bin B is provided with means operatively connected with the rearward end of the screw conveyor 23 for insuring a continuous supply of coal to the trough 14 and for completely emptying the bin. Coal, particularly when it contains an appreciable amount of slack, will not when damp flow freely into the trough 14. The coal arches over the screw conveyor or in some instances a chasm will be formed in the coal above the screw conveyor. In the novel construction shown in the drawings, reference being had particularly to Figs. 4 and 6, the bin bottom 13 is provided centrally thereof with a vertically extending bearing 32 in which is rotatably mounted a shaft 33 extending above and below the bin bottom 13.

Secured to the shaft 33 within the bin B are a number of laterally extending arms spaced a little distance above the bin bottom 13. Four arms, numbered 34, 35, 36, and 37, at right angles to each other extending successively greater distances away from the shaft 33, are shown in the drawings. The revolving arms 34, 35, 36, and 37 prevent the formation of an arch or chasm in the coal, permitting it to fall freely into the trough 14 and also push coal that rests on the bin bottom into the trough. The screw conveyor 23 takes more coal away from the rearward portion of the bin B than from its forward portion, so that another purpose of the arms 34, 35, 36 and 37 is to continuously push coal from the forward portion of the bin to the rearward portion thereof preventing depletion of coal in the rearward portion of the bin. For purpose of illustration, four rotating arms have been shown, however, where the moisture content of the coal is not excessive, fewer arms will function satisfactorily and less power is required to operate them.

In order to effect a continuous delivery of coal to the trough 14 it is only necessary that the arms 34, 35, 36 and 37 revolve very slowly and for this purpose the drive mechanism from the screw conveyor 23 to the shaft 33 includes speed reducing mechanism, best shown in Figs. 4, 6 and 12. The screw conveyor 23 is provided with an extended shaft portion 38 mounted in a bearing 39 formed with the rear wall of the trough 14 and projects rearwardly therethrough. Secured to the projecting portion of the shaft extension 38 is a crank arm 40 having a pin 41 projecting rearwardly from its free end and on which pin is loosely mounted a block 42. One end 43 of a transversely extending rod 44 is attached to the block 42 so that reciprocating movement is transmitted to the rod 44 by the screw conveyor 23 through the medium of the shaft extension 38, crank arm 40 and block 42.

The other end 45 of the rod 44 is attached to a block 46 which is mounted on the free end of an arm 47 of the pivotally mounted bell crank lever 48. The bell crank lever 48 is mounted for rotation on the vertical shaft 49 which is supported in a sleeve 50 depending from the under side of the bin bottom 13. A rod 51 is pivotally attached at one end to the free end of the other arm 52 of the bell crank lever 48. The free end of the rod 51 carries a pin 53 engaging the teeth of a large ratchet wheel 54 fastened to the shaft 33, and a spring 55 holds the free end of the rod 51 against the ratchet wheel 54. Thus, reciprocating movement of the rod 44 oscillates the bell crank lever 48 which in turn transmits reciprocating movement to the rod 51. The reciprocating movement of the rod 51 causes the ratchet wheel 54 to turn a fraction of a revolution which in turn through the shaft 33 causes the arms 34, 35, 36 and 37 to turn a small part of one revolution.

Coal is discharged by the screw conveyor 24 through the discharge opening 26 of the conduit 19 into an upturned arm of a duct 56 leading from a fan casing 57. From the duct 56, the coal is pneumatically conveyed through a coal tube 58, by means hereinafter described in detail, to the branch fitting 59 where the stream of coal is divided and delivered to the downcomers 12 and 12'. The branch fitting 59 is provided with a pivotally mounted vane 60 arranged for convenient adjustment by a handle 61 to vary the relative amounts of fuel delivered to the downcomers 12 and 12'.

Since the coal is pneumatically conveyed through the coal tube 58, there is a tendency for some of the carrier fluid to blow through the opening 26 and the conduit 19 and raise considerable dust in the bin. This is of course objectionable and the stoker is therefore designed to prevent this condition. The screw conveyor 23 can be made somewhat smaller in diameter than the screw conveyor 24, for example in a ratio of 3 to 3 1/2, since the screw conveyor 23 is working in a body of coal and will convey a greater quantity than its rated capacity. A plate 62, the lower edge of which is formed on an arc, is mounted against the inside surface of the upright wall of the bin B above the screw conveyor 23 for vertical adjustment to permit regulation of the size of the opening 15. The size of the opening 15 is regulated to keep the portions of the screw conveyors 23 and 24 within the compartment 17 completely filled with coal. With the opening 15 adjusted as described and with the backward slipping of the coal down the inclined

flight of the screw conveyor 24 the conduit 19 is filled with coal and forms an effective seal against the blowing back of the carrier fluid through the conduit 19.

For convenient installation of the stoker it may be necessary to provide bends such as at 63 in the coal tube 58 and downcomer pipes 12 and 12'. In the preferred installation overhead piping is shown through which the coal is pneumatically conveyed, however, it will be apparent that the piping can be made to extend beneath the furnace room floor to the furnace, if desired.

In the past difficulty has been experienced in pneumatically conveying wet coal and particularly wet coal containing a large amount of slack, since even a very small percent of water in the coal gradually clogs the elbows in the fuel pipe and eventually the straight sections of the pipe. This difficulty has been eliminated by convenient and efficient means in the present construction. A substantial portion of the coal tube 58 at that end receiving coal from the conduit 19 is enclosed by a casing 64 which communicates with the pipe 65 leading from the breeching 66 of the furnace F. An elbow 67 swivelly mounted on the casing 64 for movement about the vertical shaft 68 provides communication between the casing 64 and the pipe 65.

The lower end of the casing 64 communicates with a mixing box 69 through a passage 70, and a passage 71 provides communication between the mixing box 69 and an intake port of a small or auxiliary fan 72 which is operated by a small motor 73. The discharge port of the fan 72 communicates through a passage 74 with the intake port of a larger or main fan 75 housed in the fan casing 57 and operated by a large motor 76. The small or auxiliary fan 72 is not essential to successful operation of the stoker and could be omitted, however, the advantages thereof will be hereinafter explained.

The fans 72 and 75 draw hot stack gases from the breeching 66 through the pipe 65 and the casing 64 into the mixing box 69. In traversing the casing 64, the hot stack gases heat the coal tube 58 thereby drying the wet coal passing through the coal tube 58 and preventing clogging of the coal therein.

The bottom of the mixing box 69 is open to atmosphere as shown at 77, and the fans 72 and 75 draw air into the mixing box 69 where they are mixed with the hot stack gases, the mixed gases then are drawn through the fans 72 and 75 and discharged from the fan 75 into the duct 56. The mixture of stack gas and air blown through the duct 56 pneumatically conveys the coal entering the duct 56 through the opening 26 upwardly into the coal tube 58 and thence to the furnace. Thus, when wet coal is being delivered from the conduit 19, the heated mixture of air and stack gas dries the coal preventing adherence to the coal tube 58 and eventual clogging thereof.

The mixing box 69 is provided with a horizontal partition 78 extending partially across the mixing box between the hot stack gas and cold air admission ports. A vane 79, rigidly secured to a horizontal shaft 80 extending through the opposite upright side walls of the mixing box, is arranged for adjustment to any desired position about a horizontal axis by turning the hand wheel 81. By adjusting the vane 79, hot stack gases and cold air can be admitted to the fan

72 in any desired proportions to obtain the desired temperature.

The screw conveying system, consisting of the screw conveyors 23 and 24, as stated before, is operatively connected to gearing housed in the gear casing 28. The motive power for operating the screw conveying system is supplied by the motor 76 which also operates the fan 75. The drive connections between the motor 76 and the gear 30 in the gear casing 28, including means for sounding an alarm if the screw conveying system should stall, will now be described in detail, reference being had particularly to Figs. 4, 7, 8, 9 and 10.

Within a sleeve 82, extending laterally from the gear casing 28, is mounted a shaft 83 carrying a worm 84 meshing with the gear 30. A portion of the shaft 83 projects beyond the sleeve 82 and on the projecting portion is loosely mounted a pulley 85 which is rotated by a belt 86 from the motor 76. Also mounted on the projecting portion of the shaft 83 and keyed thereon, as at 87 in Figure 9, is a disc 88. The disc 88 is provided with a pin 89 extending laterally from a side face of the disc near the periphery thereof, on which pin is rotatably mounted a hook 90. The hook 90 engages a pin 91 extending laterally from the pulley 85 between the periphery and the center thereof so that the pin 91 revolves with the pulley 85 about the axis of the latter. Rotation of the pulley 85 causes, through engagement of the pin 91 by the hook 90, rotation of the disc 88, which in turn, through being keyed to the shaft 83, rotates the latter, and rotation of the shaft 83 is transmitted through the gearing in the gear casing 28 to the screw conveyor 24.

The depth of engagement of the pin 91 and hook 90 is such that any load short of stalling of the conveying system, will not cause disengagement of the pin 91 and hook 90. The depth of engagement, however, is such that when the conveying system stalls, consequently stopping the disc 88, the pin 91 is forced from engagement with the hook 90 permitting the pulley 85 to idle on the shaft 83 and thereby preventing the motor 76 from burning out.

In connection with the safety release mechanism just described, an alarm device is provided warning the attendant that the coal conveying screw has been disconnected from the motor. The attendant, after releasing the clog in the coal conveying screw, can manually re-engage the pin 91 and hook 90 whereupon the coal conveying screw is again in operative relation with the motor 76.

The alarm device, referring particularly to Figures 8, 9 and 10, includes a lever 92, pivotally attached between its ends to the hook 90, and having an arm 93 and a hammer arm 94. The lever 92 is normally held in position relative to the hook 90, as shown in full lines in Figures 9 and 10, by a spring 95 which holds the lever arm 93 in contact with the stop member 96 of the hook 90. When, by reason of the stalling of the coal conveying screw, the pin 91 is disengaged from the hook 90, as described before, a spring 97 pulls the hook 90 about its pivot 89 from its normal position to the position shown in Figure 10 and as also shown in dot and dash in Figure 9, against the stop member 98 of the disc 88. With the hook 90 in this latter position, the lever arm 93 lies in the path of the pin 91 which is still free to revolve with the pulley 85. In its travel, the pin 91 depresses the lever arm 93 against

the tension of the spring 95 thereby raising the hammer arm 94. After the pin 91 has passed over lever arm 93, the spring 95 returns the lever 92 to its original position causing the hammer arm 94 to strike the bell plate 99. Thus, each revolution of the pin 91 will cause the bell plate 99 to sound, warning the attendant that the coal conveyor screw has stalled. After removing the clog in the coal conveyor, the attendant can reset 10 the alarm device manually.

As fully explained above, the stoker is designed to prevent clogging of the fuel feed tube 58 when wet coal is pneumatically conveyed. However, should a clog occur for some reason when very 15 wet coal is being conveyed, or in starting the stoker when the coal tube is cold, the stoker is designed to automatically take care of such emergencies in the manner now to be described.

A clog control mechanism 102 is secured in any 20 convenient place, it being shown secured to the casing 64 in the drawings, see Figure 1. The clog control mechanism, referring particularly to Figs. 13, 14 and 15, includes a casing 103 having a port 104. A pipe 105, see Fig. 1, connects the port 104 with the fan casing 57 providing communication therebetween. Normally the clog control mechanism is in the position shown in Fig. 13, however, when a clog occurs in the coal tube 58, pressure builds up in the casing 57 of the fan 75, which is communicated through the pipe 105 to the casing 103 of the clog control mechanism 102, and the clog control mechanism will assume the position shown in Fig. 15. Increase 30 in pressure in the casing 103 raises the flexible 35 diaphragm 106, causing the member 107 to raise the forked lever 108 about its pivots 109. The free end of the forked lever 108 carries a contact bar 110 normally connecting the contacts 111 and 112 in the motor circuit 113. A spring 114 causes 40 the forked lever 108 to snap rapidly upward upon being raised by the member 107 thereby preventing sparking between the contact bar 110 and contacts 111 and 112. Raising of the contact bar 110 of the forked lever 108 due to increase in 45 pressure against the flexible diaphragm 106 breaks the motor circuit 113 causing the motor 76 to stop, thereby interrupting operation of the main fan 75 and the coal conveying screws 23 and 24.

50 Upward movement of the member 107 raises a stem 115 which is provided with a piston 116 working in a cylinder 117. When the member 107 drops back to the position shown in Fig. 13 due to the pressure against the under side of the 55 diaphragm 106 being relieved, the spring 118 acting against the piston 116 forces the stem 115 down, the stem 115 in turn forcing the forked lever 108 down against the tension of the spring 114, so that the motor circuit 113 will again be 60 closed. The piston 116 working in the cylinder 19, in conjunction with the ball check 100 prevents too rapid descent of the stem 115.

When the motor 76 stops, thereby stopping the fan 75, the pressure in the fan casing 57 will be 65 rapidly dissipated, even before the clog in the coal pipe 58 has been relieved, so that the forked lever 108 would be forced down, closing the motor circuit 113 and starting the fan 75 and the screw conveyors 23 and 24 before the clog is relieved. 70 The clog control mechanism is therefore provided with means preventing the intermittent starting and stopping of the motor 76 while the coal tube 58 remains clogged.

This means includes a pawl 119 arranged to 75 engage a notch 120 in the portion of the stem

115 projecting through the top wall of the clog control casing 103. When the stem 115 is raised due to pressure against the under side of the diaphragm 106, the pawl 119 will engage the notch 120, thereby holding the stem in its raised position even though the pressure against the diaphragm 106 is subsequently relieved, and thereby also preventing downward movement of the forked contact lever 103 and closing of the motor circuit 113.

In the event of a clog in the coal tube 58, the cessation of operation of the main fan 75 and the screw conveyors 23 and 24, by the clog control mechanism just described, does not affect the running of the auxiliary fan 72 which is operated by the separate motor 73. The auxiliary fan 72 continues to discharge hot stack gases which after a time dry out the coal tube 58 and the plastered coal scales off and is blown into the furnace.

In order that the fan 75 and the screw conveyors 23 and 24 may not remain idle for an extended period after the auxiliary fan 72 has dried out the coal tube and relieved the clog, means is provided that periodically, as for example every 30 minutes, attempts to start the motor 76. This means includes a time interval contactor 121. The details of the time interval contactor 121 are not shown or described since such devices are well known, it being sufficient to state that this device functions to close an electric circuit 122 at periodic intervals, as for example every 30 minutes. At the stated periodic intervals, the contact arm 123 of the time interval contactor 121 closes the circuit 122 operating a solenoid 124, which raises a lever 125 releasing the pawl 119 from the notch 120 in stem 115. Release of the pawl 119 permits the stem 115 to descend, thereby forcing the forked contact arm 108 down, in turn closing the motor circuit 113 and placing the fan 75 and the screw conveyors 23 and 24 in operation. If the clog has not been relieved by the auxiliary fan 72, pressure will again build up beneath the flexible diaphragm 106, raising the stem 115 and causing re-engagement of the pawl 119 in the notch 120. The stoker will then again be inoperative, except for the auxiliary fan 72, until the contact arm 123 again closes the circuit 122.

In many cases it is not necessary to operate the stoker continuously, sufficient fuel being delivered to the furnace by operating the stoker for a predetermined length of time at periodic intervals. To accomplish this, operation of the motor 76 may be controlled through a circuit arranged to be opened and closed through another contact arm on the time interval contactor 121. As stated before, when the motor 76 is cut out of operation, thereby stopping the main fan 75 and the coal conveying screws 23 and 24, the auxiliary fan 72, operated by the motor 73, continues to function.

With control mechanism, such as that described, for intermittently operating the stoker, it is evident that the auxiliary fan 72 maintains a circulation of hot stack gases through the coal tube 58 during the "off" periods of the stoker, thereby preventing cooling of the coal tube 58 and consequent adherence of wet coal thereto when the stoker is again placed in operation. It is apparent, therefore, that the present invention greatly minimizes the possibility of clogs in the coal tube when the stoker is operated intermittently. It is also apparent that the device will function in the same manner with other well

known types of controls that can be arranged to cause intermittent operation of the motor 75.

The invention has been described in connection with the pneumatic conveying of wet coal since it is particularly adapted to successfully convey such coal. When dry coal is being conveyed the tendency for coal to clog in the coal tube 58 is very remote so that it is not essential to utilize the hot stack gases as a carrying fluid for the coal. In such cases the vane or valve 79 in the mixing box 69 can be adjusted to a vertical position thereby interrupting the passage of hot stack gases through the mixing box 69 to the fan 72. When conveying dry coal, the motor 73 which runs the auxiliary fan 72 can be cut out of operation, since there is no tendency for the coal to clog in the coal tube 58 and there is, therefore, no necessity for maintaining a circulation of hot stack gases through the coal tube at any time whether the large fan 75 is in operation or is rendered inoperative by reason of the intermittent operation of the stoker. When the auxiliary fan 72 is cut out of operation, the large fan 75 draws in carrier fluid from the mixing box 69 through the blades of the auxiliary fan 72.

When conveying dry coal, it is not essential, as explained in the preceding paragraph, to utilize the hot stack gases as a carrier fluid. It is, however, advantageous to do so, since the hot stack gases preheat the coal, so that the finer particles are in a condition for instantaneous combustion upon entering the furnace, thereby greatly minimizing stack loss. The temperature of the carrying fluid can be regulated by adjusting the vane 79 in the mixing box 69. The carrying fluid has in practice attained a temperature of about 400° F. and as is well known preheating of coal produces changes in the physical structure of the coal rendering it in a better condition for combustion.

Since in my novel stoker, coal is pneumatically conveyed, provision has been made against escape of coal dust to the atmosphere at such places where leakage is apt to occur. A pipe 126 leads from the compartment or dust box 17 to the intake side of the fan 72, thus maintaining a suction in the dust box 17 and withdrawing the coal dust therefrom through the pipe 126. This coal dust mixes with the air and hot gases that are drawn through the stoker by the fans 72 and 75 and is discharged therewith into the coal tube 58 and thence into the furnace. A pipe 127 leads from the dust seal 29 to the dust box 17 and another pipe 128 leads from the dust seal 129, disposed about the shaft 130 of the motor 76 where it enters the casing 57 of the fan 75, to the dust box 17. A clean out door 131 is provided in the duct 56, through which foreign material in the coal that is too heavy to be pneumatically conveyed can be removed.

In order to permit convenient cleaning of the coal tube 58, it is provided with a movable portion 132. The tube portion 132 is normally secured in the position shown in Fig. 1. The opposite ends of the tube portion 132 are provided with the laterally projecting flanges 133 and 134, the flange 134 fitting closely against a laterally projecting flange 135 formed with the coal tube 58, and the flange 133 fitting closely against the forward end wall 136 of the casing 64. The bolt 137 passing through the flanges 134 and 135, and the stud 138 passing through the flange 133 into a boss formed with casing end wall 136, when loosened from pivots about which the tube portion 132 can be swung down from the position

shown in Fig. 1 to the position shown in Fig. 3. The bolt 139 passing through the flange 135 and the notch 140 in the flange 134, and the stud 141 extending through a similar notch (not shown) in the flange 133 into a boss formed with the casting end wall 136, when drawn up tight securely hold the tube portion 132 in the position shown in Fig. 1. Centering pins 142 and 143 are preferably used to insure exact register of the tube portion 132 with the coal tube 58. Thus, to drop the tube portion 132 down to the position shown in Fig. 3, it is only necessary to remove the centering pins 142 and 143 and loosen the bolts 137 and 139, and the studs 138 and 141.

In order to prevent leakage of coal dust at the adjacent ends of the tube portion 132 and the coal tube 58, the outer face of the flanges 133 and 134 are provided with the grooves 144 and 145, respectively. A pipe 146 provides communication between the grooves 144 and 145 and an opening 147 in the end wall 136 of the casing 64. The suction in the casing 64 will withdraw any coal dust that works its way into the grooves 144 and 145 at the adjacent ends of the tube portion 132 and the coal tube 58.

In Figures 16 and 17 is shown a modification of a portion of the preferred form of the stoker. In the preferred form of the invention, it will be recalled, when the screw conveyors 23 and 24 stall, the mechanism shown in Figs. 8, 9 and 10 clutches out the screw conveyors and sounds an alarm, the motor 76 and consequently fan 75, however, continue to run. In the modified form of the invention, when the coal conveyor screws stall, the motor 150, corresponding to motor 76 of the preferred construction, is cut out of operation thereby shutting off the main fan as well as the coal conveying screws. As in the preferred construction, a belt 151 runs from the motor 150 to a pulley 152. The pulley 152 is keyed to the transversely extending shaft 153, the end of the shaft 153 remote from the pulley 152 extending into a gear casing 154, corresponding to the gear casing 28 of the preferred construction.

The shaft 153 is provided within the casing 154 with a worm 155 meshing with a gear 156 which is keyed to the shaft 157, corresponding to the shaft 31 of the preferred form that drives the coal conveying screws. The end of the shaft 153 remote from the pulley 152 is mounted in a slide bearing 158 and a thrust bearing 159 is provided on the shaft 153 between the slide bearing 158 and a shoulder 160 formed on the shaft 153. A spring 161 between the adjusting nut 162 and the slide bearing 158 normally maintains the shaft 153 in the position shown in Fig. 17.

When the coal conveying screws stall, thereby stopping the gear 156, the worm 155 will continue to turn and thread itself along the teeth of the gear 156 causing the shaft 153 to move toward the left against the pressure of the spring 161. This movement of the shaft 153 is communicated to a contact member 163 through the pivoted levers 164 and 165 breaking a control circuit 166 to the motor 150 and causing it to stop. The contact member 163 thereupon closes a circuit 167 ringing a bell 168, signifying that a clog in the coal conveying screws has caused the stoker to shut down. The spring 161 is of sufficient strength to prevent the worm 155 from threading itself along the teeth of the gear 156 during normal operation of the stoker.

When the coal conveyor screws stall and the motor 150 has been shut off by the mechanism just described, the attendant may remove the

clog. The clog having been removed, the spring 161 forces the shaft 153 back toward the right, and the spring 169 will force the contact member 163 to again close the circuit 166 and operation of the motor 150 will be resumed.

I claim:

1. A stoker for a furnace including a fuel tube extending from a source of fuel supply to the said furnace, a conduit leading from a source of hot gases, said conduit enclosing a substantial portion of the length of said fuel tube, and means for creating a current of hot gases through the enclosing portion of said conduit from said source of supply and discharging all of said hot gases into said fuel tube for pneumatically conveying the fuel through said enclosed portion of said tube to the furnace.

2. A stoker for a furnace including a fuel tube extending from a source of fuel supply to the said furnace, a conduit leading from a source of hot combustion gases produced in said furnace, said conduit enclosing a substantial portion of the length of said fuel tube, and pressure fluid generating means having an intake port communicating with said conduit for producing a current of hot gases through the enclosing portion of said conduit from said source of supply and a discharge port communicating with and discharging all of said hot gases into said fuel tube for pneumatically conveying the fuel through said enclosed portion of said tube to the furnace.

3. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gases, pressure fluid generating means having an intake port communicating with said conduit for withdrawing hot gases from said source of supply and a discharge port communicating with said fuel tube for pneumatically conveying the fuel delivered thereto by said mechanical conveying means to said furnace, a common motor for operating said pressure fluid generating means and said mechanical conveying means, and means for automatically disconnecting said mechanical conveying means from said motor when said mechanical conveying means stalls without interrupting operation of said pressure fluid generating means.

4. A stoker for a furnace including a fuel tube extending from a source of fuel supply to the said furnace, a conduit leading from a source of hot gases, said conduit enclosing a substantial portion of said fuel tube, pressure fluid generating means including a main generator and an auxiliary generator, said pressure fluid generating means having intake ports communicating with said conduit for withdrawing hot gases from said source of supply and discharge ports communicating with said fuel tube for pneumatically conveying fuel through the enclosed portion of said tube to the furnace, and means for independently operating said main and auxiliary generators, said auxiliary generator constituting a booster generator for said main generator when both said generators are in operation and effecting a continued current of hot gases through the enclosing portion of said conduit for heating the enclosed portion of said fuel tube when said main generator is out of operation.

5. A stoker for delivering fuel from a source of

supply to a furnace including means for mechanically conveying fuel from said source of supply to a point remote therefrom, a fuel tube communicating at one end with said mechanical fuel conveying means and at its opposite end with said furnace, a conduit leading from a source of hot gases, said conduit enclosing a substantial portion of said fuel tube, fan means including a main fan and an auxiliary fan connected in series, said fan means having intake ports communicating with said conduit for withdrawing hot gases from said source of supply and discharge ports communicating with said fuel tube for pneumatically conveying the fuel delivered thereto by said mechanical conveying means through the enclosed portion of said fuel tube to said furnace, a common motor for operating said main fan and said mechanical conveying means, and a motor for operating said auxiliary fan independently of said main fan and said mechanical conveying means, said auxiliary fan effecting a continued current of hot gases through the enclosing portion of said conduit for heating the enclosed portion of said fuel tube when said main fan and mechanical conveying means are out of operation.

6. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gases, fan means including a main fan and an auxiliary fan connected in series, said fan means having an intake port communicating with said conduit for withdrawing hot gases from said source of supply and a discharge port communicating with said fuel tube for pneumatically conveying the fuel delivered thereto by said mechanical conveying means to said furnace, a common motor for operating said main fan and said mechanical conveying means, means for automatically disconnecting said mechanical conveying means from said motor when said mechanical conveying means stalls, and a motor for operating said auxiliary fan independently of said main fan.

7. A stoker for a furnace including a fuel tube extending from a source of fuel supply to said furnace, fan means having an intake port and a discharge port, means forming a passage from a source of hot combustion gases to the intake port of said fan means, said passage forming means enclosing a substantial portion of the length of said fuel tube, said passage forming means having an air admission opening, said fan means withdrawing commingled hot furnace gases and air from said passage forming means through said intake port, and said discharge port communicating with said fuel tube for pneumatically conveying the fuel through said enclosed portion of said tube by said commingled hot furnace gases and air to the furnace.

8. A stoker for a furnace including a fuel tube extending from a source of fuel supply to the said furnace, pressure fluid generating means having an intake port and a discharge port, means forming a passage from a source of hot gases to the intake port of said pressure fluid generating means, said passage forming means enclosing a substantial portion of the length of said fuel tube, said passage forming means having an air admission opening, said pressure fluid generating means withdrawing commingled hot gases and

air from said passage forming means through said intake port, and valvular means in said passage forming means, said valvular means being adjustable to control the relative volume of hot gases passing through said passage forming means and the volume of air entering said passage forming means through said air admission opening, said discharge port communicating with said enclosed portion of said fuel tube for pneumatically conveying the fuel through said tube by said commingled hot gases and air to the furnace.

9. A stoker for a furnace including a fuel tube extending from a source of fuel supply to the said furnace, pressure fluid generating means having an intake port and a discharge port, means forming a passage from a source of hot gases to the intake port of said pressure fluid generating means, said passage forming means enclosing a substantial portion of the length of said fuel tube between said pressure fluid generating means and said furnace, said passage forming means having an air admission opening, said pressure fluid generating means withdrawing commingled hot gases and air from said passage forming means through said intake port, and said discharge port communicating with said fuel tube for pneumatically conveying the fuel through said tube by said commingled hot gases and air to the furnace.

10. A stoker for a furnace including a fuel tube extending from a source of fuel supply to the said furnace, pressure fluid generating means having an intake port and a discharge port, means forming a passage from a source of hot gases to the intake port of said pressure fluid generating means, said passage forming means enclosing a substantial portion of the length of said fuel tube, said passage forming means having an air admission opening, said pressure fluid generating means withdrawing commingled hot gases and air from said passage forming means through said intake port, and valvular means in said passage forming means, said valvular means being adjustable to control the relative volume of hot gases passing through said passage forming means and the volume of air entering said passage forming means through said air admission opening, said discharge port communicating with said fuel tube for pneumatically conveying the fuel through said tube by said commingled hot gases and air to the furnace.

11. A stoker for a furnace including a fuel tube extending from a source of fuel supply to the said furnace, a conduit leading from a source of hot combustion gases produced in said furnace, said conduit enclosing a substantial portion of the length of said fuel tube, fan means having an intake port and a discharge port, and a compartment between and communicating with said intake port and said conduit, said compartment having an opening to atmosphere, said fan means withdrawing commingled hot furnace gases and air from said compartment through said intake port, and said discharge port communicating with said fuel tube for pneumatically conveying the fuel through said enclosed portion of said tube by said commingled hot furnace gases and air to the furnace.

12. A stoker for a furnace including a fuel tube extending from a source of fuel supply to the said furnace, a conduit leading from a source of hot combustion gases produced in said furnace, said conduit enclosing a substantial por-

tion of the length of said fuel tube, fan means having an intake port and a discharge port, and a compartment between and communicating with said intake port and said conduit, said compartment having an opening to atmosphere, said fan means withdrawing commingled hot furnace gases and air from said compartment through said intake port, and valvular means in said compartment, said valvular means being adjustable to control the relative volume of hot furnace gases and air admitted to said fan means, said discharge port communicating with said fuel tube for pneumatically conveying the fuel through said enclosed portion of said tube by said commingled hot furnace gases and air to the furnace.

13. A stoker for a furnace including a fuel tube extending from a source of supply to the furnace, a conduit leading from a source of hot gases, pressure fluid generating means having an intake port communicating with said conduit for withdrawing hot gases from said source of supply and a discharge port communicating with said fuel tube for pneumatically conveying the fuel through said tube to the furnace, a motor for operating said pressure fluid generating means and means responsive to the pressure built up by said pressure fluid generating means, when a clog occurs in said fuel tube, for cutting said motor out of operation.

14. A stoker for a furnace including a fuel tube extending from a source of supply to the furnace, a conduit leading from a source of hot combustion gases produced in said furnace, fan means having an intake port communicating with said conduit for withdrawing hot gases from said source of supply and a discharge port communicating with said fuel tube for pneumatically conveying the fuel through said tube to the furnace, a motor for operating said fan and means responsive to the pressure built up by said fan means, when a clog occurs in said fuel tube, for cutting said motor out of operation.

15. A stoker for a furnace including a fuel tube extending from a source of supply to the furnace, a conduit leading from a source of hot combustion gases produced in said furnace, said conduit enclosing a substantial portion of the length of said fuel tube, fan means having an intake port communicating with said conduit for withdrawing hot gases from said source of supply and a discharge port communicating with said fuel tube for pneumatically conveying the fuel through said tube to the furnace, a motor for operating said fan and means responsive to the pressure built up by said fan means, when a clog occurs in said fuel tube, for cutting said motor out of operation.

16. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gas, fan means having an intake port communicating with said conduit for withdrawing hot gases from said source of supply and a discharge port communicating with said fuel tube for pneumatically conveying the fuel delivered thereto by said mechanical conveying means to said furnace, means for operating said fan means and said mechanical conveying means, and means responsive to the pressure built up by said fan means, when a clog occurs in said

fuel tube, for cutting said fan means and said mechanical conveying means out of operation.

17. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gas, said conduit enclosing a substantial portion of the length of said fuel tube, fan means having an intake port communicating with said conduit for withdrawing hot gases from said source of supply and a discharge port communicating with said fuel tube for pneumatically conveying the fuel delivered thereto by said mechanical conveying means to said furnace, a common motor for operating said fan means and said mechanical conveying means, and means responsive to the pressure built up by said fan means, when a clog occurs in said fuel tube, for cutting said motor out of operation.

18. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gas, fan means including a main fan and an auxiliary fan connected in series, said fan means having an intake port communicating with said conduit for withdrawing hot gases from said source of supply and a discharge port communicating with said fuel tube for pneumatically conveying the fuel delivered thereto by said mechanical conveying means to said furnace, a common motor for operating said main fan and said mechanical conveying means, means responsive to the pressure built up by said main fan, when a clog occurs in said fuel tube, for cutting said motor out of operation, and a motor for operating said auxiliary fan independently of said main fan.

19. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot combustion gases produced in said furnace, said conduit enclosing a substantial portion of the length of said fuel tube, fan means including a main fan and an auxiliary fan connected in series, said fan means having an intake port communicating with said conduit for withdrawing hot gases from said furnace and a discharge port communicating with said fuel tube for pneumatically conveying the fuel delivered by said mechanical conveying means to said furnace, a common motor for operating said main fan and said mechanical conveying means, means responsive to the pressure built up by said main fan, when a clog occurs in said fuel tube, for cutting said motor out of operation, and a motor for operating said auxiliary fan independently of said main fan.

20. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gas, fan means having an intake port communicating with said conduit for withdrawing hot

gases from said source of supply and a discharge port communicating with said fuel tube for pneumatically conveying the fuel delivered thereto by said mechanical conveying means to said furnace, a common motor for operating said fan means and said mechanical conveying means, means for disconnecting said mechanical conveying means from said motor when the conveying means stalls, and alarm means associated with said disconnecting means arranged to be set in operation upon functioning of said disconnecting means.

21. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot combustion gases produced in said furnace, said conduit enclosing a substantial portion of the length of said fuel tube, fan means having an intake port communicating with said conduit for withdrawing hot gases from said furnace and a discharge port communicating with said fuel tube for pneumatically conveying the fuel delivered thereto by said mechanical conveying means to said furnace, a common motor for operating said fan means and said mechanical conveying means, means for disconnecting said mechanical conveying means from said motor when the conveying means stalls, and alarm means associated with said disconnecting means arranged to be set in operation upon functioning of said disconnecting means.

22. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gases, pressure fluid generating means having an intake port communicating with said conduit for withdrawing hot gases from said source of supply and a discharge port communicating with said fuel tube for pneumatically conveying the fuel delivered thereto by said mechanical conveying means to said furnace, power means for operating said pressure fluid generating means and said mechanical conveying means, means for automatically interrupting the application of power to said mechanical conveying means by said power means when said mechanical conveying means stalls and means, responsive to the pressure built up by said pressure fluid generating means when a clog occurs in said fuel tube, for rendering said mechanical conveying means and said pressure fluid generating means automatically inoperative.

23. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gases, pressure fluid generating means having an intake port communicating with said conduit for withdrawing hot gases from said source of supply and a discharge port communicating with said fuel tube for pneumatically conveying the fuel delivered thereto by said

mechanical conveying means to said furnace, a common motor for operating said pressure fluid generating means and said mechanical conveying means, means for automatically disconnecting said mechanical conveying means from said motor when said mechanical conveying means stalls and means, responsive to the pressure built up by said pressure fluid generating means when a clog occurs in said fuel tube, for automatically cutting said motor out of operation.

24. A stoker for a furnace including a fuel tube extending from a source of fuel supply to the said furnace, said fuel tube including a bend between its ends, a conduit leading from a source of hot gases, said conduit enclosing the bend in said fuel tube, and means creating a current of hot gases from said source of supply through the portion of said conduit enclosing said bend and discharging all of said hot gases into said fuel tube for pneumatically conveying the fuel through said enclosed portion of said tube to the furnace.

25. A stoker for delivering fuel from a source of supply to a furnace including means for mechanically conveying fuel from said source of supply to a point remote therefrom, a fuel tube communicating at one end with said mechanical fuel conveying means and at its opposite end with said furnace, a conduit leading from a source of hot gases, fan means including a main fan and an auxiliary fan connected in series, said fan means having an intake port communicating with said conduit for withdrawing hot gases from said source of supply and a discharge port communicating with said fuel tube for pneumatically conveying the fuel delivered thereto by said mechanical conveying means to said furnace, power means for operating said main fan and said mechanical conveying means, means for automatically interrupting the application of power to said mechanical conveying means by said power means when said mechanical conveying means stalls, and means for operating said auxiliary fan independently of said main fan.

26. A stoker for a furnace including a fuel tube extending from a source of fuel supply to the said furnace, a conduit leading from a source of hot gases, said conduit enclosing a substantial portion of the length of said fuel tube between the fuel receiving and fuel discharging ends of said fuel tube, and means for effecting a current of hot gases flowing through the said enclosing portion of said conduit from said source of hot gas supply to the fuel receiving end of said fuel tube and discharging said hot gases into said fuel tube for pneumatically conveying the fuel through said enclosed portion of said tube to the furnace.

27. A stoker for a furnace including a fuel tube extending from a source of fuel supply to the said furnace, said fuel tube including a bend between its fuel receiving and fuel discharging ends, a conduit leading from a source of hot gases, said conduit enclosing the bend in said fuel tube, and means for effecting a current of hot gases flowing through the said enclosing portion of said conduit from said source of hot gas supply to the fuel receiving end of said fuel tube and discharging said hot gases into said fuel tube for pneumatically conveying the fuel through said enclosed portion of said tube to the furnace.

NATHAN M. LOWER.
